UNITED STATES PATENT OFFICE.

MINO BOOM AND ALBERT T. BOOM, OF BLADEN, NEBRASKA.

AUTOMATIC MAIL CATCHING AND DELIVERING APPARATUS.

1,329,576.

Specification of Letters Patent.

Patented Feb. 3, 1920.

Application filed May 14, 1918. Serial No. 234,513.

To all whom it may concern:

Be it known that we, MINO BOOM and ALBERT T. BOOM, citizens of the United States, and residents of Bladen, in the county of Webster and State of Nebraska, have invented certain new and useful Improvements in Automatic Mail Catching and Delivering Apparatus, of which the following is a specification.

10 Our invention relates to improvements in mail receiving and delivering apparatus, and it consists in the constructions, combinations and arrangements herein described and claimed.

15 An object of our invention is to provide an automatic mail catching and delivering apparatus, adapted more especially for use on rural routes and is so arranged that it does not require observation to insure its 20 operation, after the various parts of the mechanism are once set.

Another object of the invention is to provide a catching and delivering apparatus for use on rural mail routes which includes 25 a truck adapted to travel over the route and which is provided with receiving and delivering boxes arranged to coöperate with combined delivery and receiving boxes disposed at stations along the route.

30 Other objects and advantages will appear in the following specification, reference being had to the accompanying drawings in which:

Figure 1 is a side elevation showing the 35 apparatus complete,

Fig. 2 is a plan view of the parts shown in Fig. 1,

Fig. 3 is a longitudinal section of the delivery box which is mounted on the truck,

40 Fig. 4 is a front elevation of the combined delivery and receiving box which is located at a station,

Fig. 5 is a longitudinal section on the line 5—5 of Fig. 4 illustrating a portion of the 45 operation when the truck-carried receiving box moves beneath the stationary box, and

Fig. 6 is a detail section of a portion of the truck-carried receiving box.

In carrying out our invention we provide 50 a truck 1 which as shown in the drawings, includes the wheels 2 which run over the tracks 3. The tracks 3 extend along the

rural mail route and may be laid in any desired manner. One way of laying the tracks 3 consists in providing extra cross arms 4 on the poles 5, and supporting the tracks on these cross arms.

It is even conceivable that the tracks 3 may be dispensed with and the truck 1 be of such a design that it may simply run on the ground. In this event, the receiving and delivering mechanism may be so arranged with a certain latitude of movement that the usual unevenness of the ground may readily be compensated for. It is not desired, however, to unduly emphasize this feature since as stated before, it is the present intention to provide the tracks 3 upon which the truck 1 runs.

Obviously the truck 1 will be propelled by 70 a suitable motor. The truck is pivoted in the middle at 6 in order that it may more readily turn curves in the track. Located at the front of the truck is a mail receiving box 7.

The box 7 has lids 8 which are hinged at 75 9 and have extending portions 10 beyond the hinges. These extending portions are arranged to be engaged by lid guides 11 on opposite sides of the track.

A common pivot 12 located beneath the track joins the lid guides 11 at the front. The lid guides 11 bend downwardly at the rear and across beneath the track where they are supported in the normal position illustrated in Fig. 1 by the end 13 of a latch bar 14. The latch bar 14 is mounted in suitable guides wherein it is capable of sliding forwardly against the tension of a spring 15. The spring 15 is disposed in the region of 80 90 an abutment 16 which is adapted to be struck by the forward portion of the truck 1 in order to move the latch forwardly.

Obviously a depending finger such as 95 illustrated in dotted lines in Fig. 1, may be employed to move the latch forwardly so as to disengage the rear end of the lid guides. This function is accomplished only after the receiving box 7 has advanced to approximately the extremity of the lid guides. 100 When this has occurred, the lids 8 will have been moved to the vertical position illustrated in Fig. 5. The function of the lid guides will then have been completed, and

being released through the agency of the abutment 16 and depending portion of the truck, drop down by swinging on the pivot 12 and remain out of the way until they are 5 reset.

The lids 8 are normally held closed on the receiving box 7 by springs 17 which are disposed substantially as shown in Fig. 6. The lids are made to open by the guides 11 10 against the tension of the springs 17, and when the lids are released by the guides, the springs cause the lids to close.

A combined delivery and receiving box 18 is fixedly mounted at each station along the 15 rural mail route, and this box as its name implies, is arranged to perform the combined functions of first delivering outgoing mail from the station to the moving truck and then receiving incoming mail from the 20 truck which is intended for the station. The box 18 has a hinged bottom 19 which is normally held up by a catch 20.

The catch 20 is pivoted at 21 to a sliding trip plate 22. The trip plate slides in guides 25 23 on the rear wall of the box 18. The plate 22 has a pair of trips 24 which are pivoted at 25 and extend downwardly beyond the pivot and in the path of the front edge of the receiving box 7.

30 The trips 24 are struck by the front edge of the receiving box and for this purpose are rounded as shown. The trips 24 are in the nature of levers which include the upper ends lying beneath the side portions of the 35 catch 20. A spring 26 carried by the trip plate, presses in on the catch 20 and when the trips 24 are engaged as just explained, the catch 20 is moved rearwardly against the tension of the spring 26 and thus releases the 40 bottom 19 which was formerly supported on the catch.

In the initial part of the downward movement of the bottom 19, the rear edge is 45 temporarily caught on the trips 24 as shown in Fig. 5. As soon as the front edge of the moving box 7 advances beneath the trips 24, they fly backwardly being impelled by the spring 26, thus releasing the bottom 19 which then drops down inside of the receiving 50 box 7 and discharges whatever outgoing mail may have been deposited into the box 18.

A lug 27 formed on the catch 20 occupies either of a pair of holes 28 in the rear wall 55 of the box 18. A spring 29 attached between the box 18 and a lug 30 on the trip plate 22, tends to pull the plate upwardly. This is prevented by the engagement of the lug 27 with the lower hole 28 when the trip 60 is set. Similarly, the accidental downward movement of the trip plate to the setting position is prevented by the engagement of the lug 27 with the upper hole 28. The lug 27 is released from the lower hole simultaneously with the operation of the trips and

catch and in the same operation, the spring 29 pulls the trip plate to the upper position where this portion of the mechanism remains inactive until it is manually reset.

Lids 31 pivoted on the box 18 and provided with extending portions 32, are arranged to be subsequently opened to receive incoming mail. Springs 33 normally keep the lids closed. The bottom 19 is again automatically closed upon the opening of the 75 lids 31, by a connection 34 between said lids and the bottom.

Mounted on standards 35 on the truck 1 is a delivery box 36 in which mail for the 70 different stations along the route is placed. The standards 35 have arms 37 which are intended to engage the extending portions 32 and open the lids 31 substantially in the same manner as the lids 8 of the box 7 are opened. The mail for the various stations 85 is separated in the delivery box 36 by a plurality of platforms 38. The platforms are held spaced apart by legs 39 as shown in Fig. 3. A rod 40 at the rear guides the platforms downwardly and to a rearward 90 and inoperative position. For this purpose the rod includes a rounded portion at the bottom.

The lower platform 38 is supported by the nose of a pivoted trip 41 at the front and 95 by small lugs 42 at the back. In advancing toward the box 18 of the rural station, the trip 41 eventually strikes the rear edge of said box which thus rocks in a clockwise direction on its pivot. The nose then 100 moves from beneath the lowermost platform 38 and releases it, whereupon the platform drops down.

At the same time, the adjacent portion of the nose bears against the lower end of a 105 pivoted detent 42 which is in normal disengagement with the next platform. However, upon said engagement of the trip with the detent, the nose of the detent is made to move inwardly beneath the next platform 110 and temporarily support it so that it too will not drop down with the lowermost platform 38.

Upon swinging downwardly, the platform 38 readily disengages from the lugs 42 at 115 the rear because there is but a short contacting portion between the two. Upon the continued advancement of the delivery box 36, the now free platform 38 is caught by a pair of arms 43 at the front of the box 18 120 and is carried up into an inactive position at the rear of the delivery box. The platform is here supported by a catch 44 which is mounted on a rod 45 from the box 36. The position of one of the platforms is indicated in dotted lines in Fig. 3. A spring 46 engages the detent 42 and keeps both the detent and the trip 41 in the normal position indicated. A lid 47 on the box 36 serves to keep out moisture and dirt. 130

The arms 43 at the front of the box 18, are pivoted at 48 from whence they extend rearwardly and receive one end of a spring 49 which tends to normally hold the 5 arms up. This spring also enables a certain amount of yielding movement of the arm to which it is connected.

The operation of the device may be briefly summed up as follows: The tracks 3 extend 10 throughout the length of a rural mail route passing by the stations which it is intended to serve. The stations along the route will be known either by name or number and there will be one compartment between the 15 platforms 38 for mail intended for these stations in succession. For instance, mail for station No. 1 will be placed below the lowermost platform and the one next following. Mail for station No. 2 will be placed 20 between the second and third platforms. If no mail is intended for station No. 3, the space between the third and fourth platforms will remain empty, and so on throughout the height of the truck-carried delivery 25 box 36.

The occupant of a station places outgoing mail into his box 18. When the truck 1 reaches the station, the receiving box 7 advances beneath the lid guides 11 whereupon 30 the lids 8 are raised and the box 7 moves under the box 18 with the lids in the open position. The trip and catch mechanism is now operated so that the lid 19 is released inside of the box 7 and the outgoing 35 mail just mentioned is discharged into the receiving box 7.

This action having been completed, the arms 37 ride upon the portions 32 of the lids 31 on the box 18 and cause these lids to 40 open. The trip mechanism 41 and 42 of the box 36 is now operated so that the lowermost platform 38 is released. The mail intended for this station is thus discharged into the box 18. But before this discharging 45 function occurs, the bottom 19 is first returned to the original closed position simultaneously with the opening of the lids 31. This occurs through the agency of the flexible connection 34 and also occurs before the trip mechanism 41 operates.

If the occupant of a station has no outgoing mail for the next collection, the trip plate 22 is left in the uppermost position. Consequently the front edge of the receiving 55 box 7 cannot strike the trips 24 and thus the bottom 19 is not released. The lids 31, however, are opened each time and if no mail is intended for the particular station, a platform below an empty space above 60 simply drops down and is moved to the inactive position at the rear in the manner already fully explained.

It is to be observed that in all of its 65 actions the mechanism described herein is automatic. The device is intended to per-

form its functions without the necessity of observation. The delivery box 36 is loaded at the post office and the act of distributing the mail is performed automatically throughout the length of the route. 70 While the device is intended primarily for distributing mail in rural communities, the same principles may be applied in other connections.

While the construction and arrangement 75 of the device as herein described is that of a generally preferred form, obviously modifications and changes may be made without departing from the spirit of the invention or the scope of the claims.

We claim:

1. The combination in a mail handling device, of a stationarily held delivery box, a lid normally closing the bottom, a catch holding the lid in the closed position, engageable means adapted to displace the catch and temporarily hold the lid from dropping, a traversing receiving box, lids normally closing said box, and means arranged to engage portions of said lids to 80 raise them and expose the front edge of said box, enabling the engagement of said edge with said engageable means to first release and temporarily hold the bottom lid, said lid subsequently dropping into the receiving box when the receiving box edge passes beyond said engageable means.

2. The combination in a mail handling device, of a delivery box, a hinged bottom for the box, means holding the bottom closed 100 and including a trip member, a receiving box arranged to move beneath the delivery box, lids normally closing the receiving box, means including lid guides arranged to engage portions of said lids to raise them before the receiving box moves beneath the delivery box, said trip member being in position to be engaged by the then exposed edge of the receiving box to obtain the release of the hinged bottom, and means for drawing 105 said holding means and trip member out of the zone of movement of said box edge.

3. The combination in a mail handling device, of a stationary combined mail delivery and receiving box, a hinged bottom, 115 hinged lids for the top, a connection between the bottom and top lids, a traversing truck having a lidded receiving box arranged to pass under the stationary box, a relatively fixed lid guide arranged to engage and open 120 the lids of the receiving box, means normally holding the hinged bottom closed and arranged to release said bottom upon engagement therewith with the then exposed front edge of the receiving box, means engageable by the truck for releasing the lid guide into an inactive position, means carried by the truck for engaging the stationary box top lids to open them and simultaneously close the bottom, and a delivery 125 130

box carried by said truck subsequently moving over the then open receiving box to discharge mail therein.

4. The combination in a mail handling device, of a stationary combined mail delivery and receiving box, a hinged bottom, hinged lids for the top, a connection between the bottom and top lids, a traversing truck having a lidded receiving box arranged to pass under the stationary box, a relatively fixed lid guide arranged to engage and open the lids of the receiving box, means normally holding the hinged bottom closed and arranged to release said bottom upon engagement therewith with the then exposed front edge of the receiving box, means engageable by the truck for releasing the lid guide into an inactive position, means carried by the truck for engaging the stationary box top lids to open them and simultaneously close the bottom, a delivery box carried by said truck subsequently moving over the then open receiving box to discharge mail therein, and means embodied in said delivery box arranged to engage the open stationary receiving box, for releasing a quantity of mail for discharge into said receiving box.

5. The combination in a mail handling device, of a stationary receiving box, lids normally closing the box, a traversing truck having a delivery box movable over a receiving box, means located in advance of the delivery box for opening the lids, a plurality of platforms arranged one above the other in the delivery box, means supporting the platforms in spaced relationship, and means carried by the delivery box arranged to engage said receiving box to release the lowermost platform for the discharge of the mail supported thereon and to catch the platform above to prevent it from dropping.

6. The combination in a mail handling device, of a stationary receiving box, lids normally closing the box, a traversing delivery box arranged to move over the receiving box, means located in advance of the delivery box for opening the lids, a plurality of platforms disposed in spaced relationship in the delivery box, a guide for said platforms, a rearwardly disposed catch, means including a trip and a detent arranged to coact with the receiving box for releasing the lowermost platform and holding the next platform from dropping, and means located in front of the receiving box for subsequently transferring the released platform around the guide into contact with the catch.

7. The combination in a mail handling

device, of a traversing mail receiving box, a wheeled truck supporting the box and arranged to move over a track, lids normally closing said box and provided with projecting portions, means including lid guides pivotally mounted beneath the track and arranged to engage said projecting portions and raise the lids, and a catch bar engaging said means in a normally operative position, and including an abutment arranged to be engaged by a portion of the truck to release said means and permit it to rock to an inoperative position.

8. A mail handling apparatus including a stationary combined delivery and receiving box, a hinged bottom for the box, a catch supporting the bottom, a vertically slidable trip plate forming the mounting for the catch, pivoted trips carried by said plate including a lower engageable portion and an upper portion arranged to move the catch from beneath the bottom, means holding the trip plate in the set position, and means for drawing the trip plate up into an inoperative position upon the engagement of said trip and the release of said holding means.

9. A mail handling apparatus including a stationary combined delivery and receiving box, a hinged bottom, a catch normally supporting the bottom, engageable trips adapted upon engagement to displace the catch and release the bottom, hinged lids for the top of the box, projected portions included in said lids arranged to be engaged to open the box, and a connection between said lids and the hinged bottom to simultaneously draw the bottom to the closed position while the lids are moving to the open position.

10. A mail handling apparatus comprising a stationary combined delivery and receiving box having a pair of openings in the rear wall, a hinged bottom for the box, a slideable trip plate, trips pivoted on said plate including portions extending below and above the pivots, a catch pivoted on the plate and arranged to support the bottom, means pressing the trips and catch into the active positions, said catch including a portion in contact with the upper portions of said trips and being provided with a lug occupying the lower opening when the trip is set, and means arranged to draw the trip into an inoperative position to enable the lug to enter the upper opening, when the catch is displaced upon operation of the trips.

MINO BOOM.
ALBERT T. BOOM.
